Primary Examiner — Kendra Leslie Hamilton(74) *Attorney, Agent, or Firm* — Taft Stettinius & Hollister LLP(57) **CLAIM**

The ornamental design for a pacifier simulative of a dog, as shown and described.

DESCRIPTION

FIG. 1 is a top plan view of a pacifier simulative of a dog showing our new design;

FIG. 2 is a right side elevation view thereof;

FIG. 3 is a front elevation view thereof;

FIG. 4 is a left side elevation view thereof;

FIG. 6 is a rear elevation view thereof;

FIG. 7 is a top, rear, right perspective view thereof; and,

FIG. 8 is a top, front, right perspective view thereof.

The broken lines shown in the figures are for the purpose of illustrating portions of the pacifier simulative of a dog that form no part of the claimed design.

1 Claim, 2 Drawing Sheets(56)
